(57) **CLAIM**

The ornamental design for an adjusting assembly for fixing glass as shown and described.

DESCRIPTION

FIG. 1 is a front view of an adjusting assembly for fixing glass;

FIG. 2 is a left side view thereof;

FIG. 3 is a right side view thereof;

FIG. 4 is a rear view thereof;

FIG. 5 is a bottom view thereof;

FIG. 6 is a top view thereof;

FIG. 7 is a cross-sectional view along the line 7-7 in FIG. 6;

FIG. 8 is a perspective view thereof;

FIG. 9 is a perspective view of component 1 of the adjusting assembly for fixing glass;

FIG. 10 is a perspective view of component 2 of the adjusting assembly for fixing glass;

FIG. 11 is a perspective view of component 3 of the adjusting assembly for fixing glass; and,

FIG. 12 is a cross-sectional view of the adjusting assembly for fixing glass arranged in a housing.

The adjusting assembly for fixing glass is a combination of components 1, 2 and 3.

The portions indicated by broken lines are to show environment and form no part of the claimed design.

1 Claim, 8 Drawing Sheets
